UNITED STATES PATENT OFFICE.

FREDERICK V. JONES, OF ZYLONITE, MASSACHUSETTS, ASSIGNOR TO THE
UNITED ZYLONITE COMPANY, OF SAME PLACE.

DESIGN FOR A TOILET-COMB.

SPECIFICATION forming part of Design No. 20,071, dated August 5, 1890.

Application filed July 9, 1890. Serial No. 358,202. Term of patent 7 years.

To all whom it may concern:

Be it known that I, FREDERICK V. JONES, a citizen of the United States, residing at Zylonite, in the county of Berkshire and State of Massachusetts, have invented and produced a new and original Design for Toilet-Combs, of which the following is a specification.

This design has for its object to provide a novel, ornamental, and handsome toilet-comb; and the leading feature thereof resides in a comb having two sets of teeth of different attenuation extending from a comb-back, the inner and outer edges of which are curved in the arcs of circles.

The design is illustrated in the accompanying drawing, in which the figure is a side elevation of a flat toilet-comb embodying my design.

In the drawing, the numerals 1 and 2 indicate the two sets of comb-teeth of different attenuation extending from the inner edge 3

of the comb-back 4. The inner edge 3 and the outer edge 5 of the comb-back are curved uniformly in the arcs of circles, and the back may be ornamented by ribs 6 and leaves or 25 branches 7. The points of the teeth are in a curved line struck from a circle of greater radius than the outer edge 5, whereby the comb is what may be termed "meniscus-shaped."

What I claim is—

The design for a comb having two sets of teeth of different attenuation extending from a comb-back, the inner and outer edges of which are curved in the arcs of circles, substantially as shown and described.

In testimony whereof I have affixed my signature in presence of two witnesses.

FREDERICK V. JONES.
